DESIGN FOR A DOLL

Olivia A. Dunn, Orange, N. J.

Application July 30, 1941, Serial No. 102,571

Term of patent 14 years

To all whom it may concern:

Be it known that I, Olivia A. Dunn (sometimes known as Antonia Dunn), a citizen of the United States and a resident of Orange, county of Essex, and State of New Jersey, have invented a new, original, and ornamental Design for a Doll, of which the following is a specification, reference being had to the accompanying drawing, forming part thereof, in which—

I claim:

The ornamental design for a doll, substantially as shown.

OLIVIA A. DUNN.
